Primary Examiner — Mary Ann Calabrese(74) *Attorney, Agent, or Firm* — Abbey A. Lopez; Amy I. Ahn-Roll(57) **CLAIM**

The ornamental design for a label, as shown and described.

DESCRIPTION

The FIGURE is a front plan view of a label.

The broken line showing of environmental structure in the FIGURE is for illustrative purposes only and forms no part of the claimed design.

1 Claim, 1 Drawing Sheet(56)
